(57) **CLAIM**

The ornamental design for a front cover for a printer, as shown and described.

DESCRIPTION

FIG. 1 is a top front, left side perspective view of a front cover of a printer showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a rear elevational view thereof.

The broken lines in the drawing are for illustrative purposes only and form no part of the claimed design.

The bottom of this printer normally rests on a surface and is not seen nor intended to be seen as a part of my new design.
